his Attorney.

UNITED STATES PATENT OFFICE.

ALBERT T. FAY, OF MINNEAPOLIS, MINNESOTA, ASSIGNOR TO ANTON HUHN, OF MINNEAPOLIS, MINNESOTA.

WHEAT-HEATER.

1,258,326.

Specification of Letters Patent.

Patented Mar. 5, 1918.

Application filed March 10, 1917. Serial No. 153,995.

To all whom it may concern:

Be it known that I, ALBERT T. FAY, a citizen of the United States, residing at Minneapolis, in the county of Hennepin and State 5 of Minnesota, have invented certain new and useful Improvements in Wheat-Heaters, of which the following is a specification.

My invention relates to wheat heaters, and has for its object to provide a wheat heater 10 of the type which employs a substantially horizontal rotating cylinder with a closure at the grain admission end of said cylinder such as to form a permanent seal to permit any leakage of grain back through the joints 15 between the stationary and moving parts at said receiving end.

The full objects and advantages of my invention will appear in connection with the detailed description thereof, and are particularly pointed out in the claims.

In the drawings, illustrating the application of my invention in one form,—

Figure 1 is a transverse sectional view of a wheat heater embodying my invention, 25 looking through the same toward the receiving end thereof. Fig. 2 is a fragmentary side elevation sectional view through the receiving end of the heater. Fig. 3 is a sectional detail much enlarged.

As illustrated, a cylinder 10 is supported 30 in rotating relation by rollers 11 which engage metal bands 12 on the cylinder, said rollers 11 being journaled upon end frame castings of which the casting 13, at the grain receiving end of the wheat heater, is shown. This casting is provided with legs 14 and 15 and a central body portion 16. This body portion 16 is provided with an inwardly extending cylindrical drum member 17 through 40 which extends obliquely a grain delivery spout or chute 18. The interior of cylinder 10 is provided with blades 19 which, receiving the grain, as the cylinder rotates, lifts the grain to the upper portion of the cylinder and pours it down through a battery of heated pipes, repeated contact with which heats the grain to the desired temperature. A few only of the heated pipes 20 are shown which extend through the inner wall 21 of 50 the drum 17 and are thereby supported and in turn support the battery of pipes in a well known manner.

The end of rotary drum 10 is partly closed by an annular plate 22 having a central circular opening 23 which is in the plane of the

inner wall 21 of the drum 17 and is spaced a suitable distance therefrom. An annular flange or lip piece 24 is rigidly secured by rivets 30 or other suitable means to a ring 25 which fits tightly around drum 17. The 60 ring 25 is driven upon drum 17 so as to bring the lip 24 exactly into the plane of plate 22 and the ring is preferably held in non-turning relation to drum 17 by a key or keys 31.

As before stated, the plate 22 and the lip 65 24 are in the same plane, and the circular edges thereof approach quite close to one another but are spaced a sufficient amount, as indicated at 26, to permit a requisite amount of relative approaching and receding movement, as the movable plate 22 rotates with cylinder 10 about the immovable flange 24. Secured to plate 22 adjacent the circular edge 23 thereof, are a pair of annular members 27 and 28 which members overlap and 70 straddle the lip 24, and are held in close engagement therewith as they rotate with plate 22 and cylinder 10.

The advantages of my invention will be obvious. The drum-face 21, annular lip 24, 80 and annular plate 22 form a plane-faced closure to the receiving end of cylinder 10 in which the portion 21—24 is stationary, and the portion 22 is rotary. A space between them 26, sufficient to permit all necessary 85 relative movements, is tightly sealed against escape of grain by the annular pieces 27—28 which straddle the lip 24 and are secured to move with the plate 22. It follows that all grain which enters the cylinder through the 90 chute 18, and which is thereafter violently agitated and thrown around and about in the cylinder by the blades 19, must remain in the cylinder as the joint between the moving portion and the stationary portion of the 95 end wall of the cylinder is, at all times, tightly sealed.

I claim:

1. A wheat heater comprising an end support and a substantially horizontal cylinder 100 rotatably supported at one end thereby, said end support being provided with a grain admission spout extending through the same, means closing the end wall of the cylinder adjacent said end support comprising 105 a member rotating with the cylinder and a member held stationary upon the end support, and means continuously sealing, in grain tight relation, the adjoining portions of said movable and stationary members. 110

2. A wheat heater comprising an end support and a substantially horizontal cylinder rotatably supported at one end thereby, said end support being provided with a grain admission spout extending through the same, means closing the end wall of the cylinder adjacent said end support comprising a member rotating with the cylinder and a member held stationary upon the end support, and a pair of members secured to the movable member to rotate therewith, straddling the stationary member, and continuously sealing in grain tight relation the adjoining portions of the movable and stationary members.

3. A wheat heater comprising an end support and a substantially horizontal cylinder rotatably supported at one end thereby, said end support including a closed inwardly extending drum having a grain admission chute extending obliquely through the same, an end wall for the cylinder comprising a member secured thereto and movable therewith, and a stationary member secured to the drum in the plane of the movable member, and means continuously sealing in grain tight relation, the adjoining portions of said movable and stationary members.

4. A wheat heater comprising an end support and a substantially horizontal cylinder rotatably supported at one end thereby, said end support including a closed inwardly extending drum having a grain admission

chute extending obliquely through the same, an end wall for the cylinder comprising an annular plate secured to the cylinder and movable therewith, and an annular plate fast with the drum and extending in the plane of the first named plate, and a pair of annular members secured to the rotating plate and straddling the stationary plate for continuously sealing in grain tight relation the adjoining edges of said rotating and stationary plates.

5. A wheat heater comprising an end support and a substantially horizontal cylinder rotatably supported at one end thereby, said end support including a closed inwardly extending drum having a grain admission chute extending obliquely through the same, an end wall for the cylinder comprising the inner end wall of the drum, an annular plate secured to the drum in the plane of said drum wall, an annular plate secured to the cylinder and extending in the plane of said first named plate and drum wall with the inner edge thereof spaced from the edge of said first named plate, and a pair of annular members secured to the rotating cylinder plate and straddling the stationary plate for continuously sealing in grain tight relation the adjoining edges of said rotating and stationary plates.

In testimony whereof I affix my signature.

ALBERT T. FAY.
